HASP FITTINGS FOR BOXES OR LUGGAGE BAGS

Charles William Blake Cheney, deceased, late of Olton, England, by Francis Martin Tomkinson, Birmingham, Howard William Cheney, Shipton-on-Stour, and Gordon Merrick Sherwood, Birmingham, England, executors, assignors to C. W. Cheney & Son Limited, Birmingham, England, a corporation of Great Britain

Filed Feb. 9, 1960, Ser. No. 7,564
10 8 Claims. (Cl. 292—281)

This invention relates to a hasp fitting for luggage and like boxes comprising a body part and a lid part which have a predetermined capacity.

A hasp fitting to which the invention relates is of that kind comprising an attachment plate and a spring loaded hasp, provided with a staple or stud, hinged to the plate on a fixed axis, so that the hasp can swing under the action of its spring away from the attachment plate, and can be moved against its spring in proximity to the attachment plate, these positions being applicable respectively to the release position and the fastened position of the hasp with respect to a co-operative fastening.

These hasp fittings are mass produced as sheet metal pressings and are assembled by unskilled labour in order to satisfy public demand for the articles at an economic price. When assembled on luggage, the fittings are subject to rough usage and in the release position the sole support of the hasp is its hinge. This has been found to be a serious disadvantage in practical use because the hasp, which may vary in its length dimension, becomes forced out of alignment with the attachment plate and as a result the stud or staple becomes disaligned in relation to the fastening member; sometimes the hinges are damaged, twisted or strained so that for one reason or another the hasp fittings become either useless or inefficient.

It is, therefore, most desirable to find, and it is an object of this invention to provide, a simple solution to the problem whereby the risk of damage to the hasp by rough usage can be prevented or considerably reduced without increasing the cost of production and assembly.

According to the present invention, a hasp fitting of the kind hereinbefore specified has side walls which project above the outer surface of the attachment plate and which fit within corresponding side walls of the hasp which is hollow, whereby the side walls on the attachment plate serve as opposing buttress abutments to the corresponding side walls of the hasp and operate to prevent lateral displacement of the hasp whatever its angular position.

According to one form of construction of the invention the attachment plate has confronting side walls projecting above the upper surface of said plate, these walls being formed by piercing and raising the plate at two positions, whereby two buttress walls are provided which are perpendicular to the plane of said plate. These walls serve as rigid guides which fit within corresponding side walls of the hollow hasp which is pivoted near one end to the said plate. The result is that the side walls of the said plate serve as abutments to the hasp and operate to prevent lateral displacement thereof whatever the angular position of the hasp.

In order that the invention may be thoroughly understood, a satisfactory form of construction of hasp fitting according to the invention especially applicable to attach cases and the like luggage is illustrated, by way of example, on the accompanying drawing, in which—

FIG. 1 is a perspective view of the hasp fitting illustrated as fastened to a co-operative fastener, the hasp being partly broken away for clarity.

FIG. 2 is an elevation of FIG. 1.

2

FIG. 3 is a section of FIG. 2 taken on the dotted line 3—3.

FIG. 4 is a section of FIG. 2 taken on the dotted line 4—4.

As will be observed in the drawing, the hasp fitting comprises an attachment plate 5 formed with a low boundary wall 6 and holes 7 for use in fastening the attachment plate, as by rivets, to a lid 8 of a box of predetermined capacity of which the body having a fastening member 11 is indicated at 9. The attachment plate 5 has confronting side walls 10 which project above its outer surface 12, the walls 10 being formed by piercing and raising the plate 5 at two spaced positions thereby providing two perpendicular buttress walls 10. A spring loaded hasp 12, provided with a staple or stud 22 to releasably engage the fastener 11, is constructed as a hollow, sheet metal pressing including a body 13 and confronting integral side walls 14 embracing the walls 10, the upper part of the walls 14 being formed with alike integral tongues 15 which are hinge-jointed to the attachment plate 5. The hinge is provided in a very simple manner by inserting the tongues 15 through alike slots 16 in the attachment plate 5 and bending the tongues inwardly adjoining the inner surfaces of the walls 10 to form a U-shaped hinge 17. It will be seen that the confronting side walls 10 of the attachment plate 5 fit within the corresponding side walls 14 of the hollow hasp 12, the side walls 10 serving as opposing buttress walls to the walls 14 so that in ordinary use lateral displacement of the hasp relative to its hinge 17 whatever its angular position, is resisted by the buttress wall 10. A torsion spring 18, arranged within the hollow hasp 12, biases the latter into its position of release away from the attachment plate 5, indicated by the arrow FIG. 3, and maintains the hinge connection 17; one limb 19 of the spring abuts against the surface 12 of the attachment plate 5 and the limb 20 abuts against the inner surface of the body 13. The release position of the hasp 12 under the torque of the spring 18 is limited by the abutment of the hinged end 21 with the adjacent part 12 of the attachment plate 5.

The manner in which the staple or stud 22 is secured to the hasp 12 forms no essential part of the present invention. Conveniently, the staple 22 is carried by a sheet metal mounting plate 23 secured to the interior of the hasp 12 by the provision of opposite integral ears 24 on the walls 14 which are folded inwardly and clinched into engagement with opposite side flanges on the plate 23.

It will be appreciated from the above description that a very inexpensive and easily manufactured hasp fitting is provided which offers the important advantages of supporting the hasp in correct relationship to its attachment plate and thus avoid the disadvantages above referred to.

What is claimed is:

1. A hasp fitting comprising an attachment member and a hasp member, one of said members having two spaced side face portions facing in opposite directions, each of said side face portions extending between an outer edge portion and an inner edge portion thereof, the other one of said members having two side walls respectively adjacent said side face portions, each of said side walls facing the adjacent side face portion in a respective one of said directions, and a body portion rigidly connecting said side walls; a tongue on each of said side walls, said tongues each having a substantially U-shaped cross section in a plane parallel to said opposite directions and movably receiving a respective one of said inner edge portions within the bight of said U-shape for pivotal movement of said hasp member toward and away

from said attachment member; and stop means for limiting said pivotal movement.

2. A hasp fitting as set forth in claim 1, wherein said side face portions are facing away from each other and said body portion is opposite said outer edge portions, corresponding elements of said body portion and of said attachment member constituting said stop means for limiting pivotal movement of said hasp member toward said attachment member.

3. A hasp fitting as set forth in claim 1, further comprising spring means permanently urging said hasp member to move pivotally away from said attachment member.

4. A hasp fitting as set forth in claim 1, said other member further including a terminal portion extending intermediate said side walls, said tongues defining the pivoting axis of said other member, said terminal portion being radially spaced from said axis, and said stop means including a portion of said one member arranged for abutting cooperation with said terminal portion to limit pivotal movement of said other member relative to said one member.

5. In a hasp fitting, in combination, an attachment plate having an outer face; two side wall members on said outer face and extending outward therefrom in substantially parallel spaced alignment; a hollow hasp member having a body portion and two side portions extending in a direction substantially perpendicular to said body portion and spaced from each other to receive said side wall members therebetween; and a tongue extending from each of said side portions in a direction away from said body portion, said outer face being formed with apertures

on either side of each of said wall members, each of said tongues freely passing through one of said apertures on one side of a corresponding wall member in a direction inward of said outer face, and through another one of said apertures on the other side of said corresponding wall member in a direction outward of said face, whereby said hasp member is pivoted to said attachment plate about an axis passing through said tongues.

6. In a hasp fitting as set forth in claim 5, said side wall members being integral with said attachment plate and extending therefrom in a direction substantially perpendicular to said outer face.

7. In a hasp fitting as set forth in claim 5, cooperating abutment means on said hasp member and on said attachment plate for limiting pivoting movement of said hasp member about said axis.

8. In a hasp fitting as set forth in claim 5, attaching means on said attachment plate for securing the same to one member of a pair of members to be connected by said hasp fitting, and a locking member on said hasp member for releasably securing said hasp member to the other member of said pair.
